UNITED STATES PATENT OFFICE.

GEORGE S. STRONG, OF NEW YORK, N. Y.

SMOKE-BOX.

SPECIFICATION forming part of Letters Patent No. 425,267, dated April 8, 1890.

Application filed August 14, 1889. Serial No. 320,748. (No model.)

To all whom it may concern:

Be it known that I, GEORGE S. STRONG, of New York city, New York, and a citizen of the United States, have invented certain Improvements in Smoke-Boxes for Locomotives, of which the following is a specification.

My invention consists of certain improvements in the construction of smoke-boxes for furnaces, more especially locomotive-furnaces.

In the accompanying drawings, Figure 1 is a vertical section of a smoke-box of a locomotive, illustrating my improvements. Fig. 2 is a front elevation, and Fig. 3 is a plan view illustrating the construction of the door-hinge.

Referring to Fig. 1, A represents the front tube-sheet of the boiler, and B the front plate of the locomotive, which I prefer to form of sheet-steel. D is the exhaust-nozzle. E is the petticoat-pipe, with adjustable head e, and F is the chimney. Around the lower part of the petticoat-pipe E is placed a transverse screen S, of perforated metal or wire-gauze, resembling in shape somewhat the bridge-wall of a furnace. The petticoat-pipe passes up through the center of this "bridge-wall" spark-arrester. Behind the spark-arrester screen is a discharge-outlet s, leading to a receptacle for the sparks. Around the upper part of the pipe E is a corresponding inverted bridge-wall screen of perforated metal or wire-gauze s'.

I prefer to construct the body of the door on the front part of the smoke-box of sheet metal, with an annular flange or rim g to fit over the outwardly-projecting flange b around the door-opening in the front plate of the smoke-box. This flange b is either made conical or flaring, as illustrated in Fig. 1, so that when the door is pressed down upon it the flange of the door will embrace and form a tight joint with the flaring portion of the flange upon the front plate. The door has a double hinge H, Figs. 2 and 3, by means of pins h passing through lugs i on the front plate and lugs j on the door and through an intermediate hinge-piece k. If the front plate of the smoke-box and the door are formed of sheet-steel, the lugs i may be punched up in

one piece with the front plate and the lugs j 5c in one piece with the door. To close the door tight and to lock it when closed, I prefer to use internal bolts L, (four in the present instance,) pivoted to a central disk l and guided near their outer ends in lugs l', carried by the 55 door. The outer ends of the bolts are preferably beveled, as shown in Fig. 1. The disk l is carried on the inner end of a screw-stem M, passing through a threaded opening in a casting m, carried by the door, and to this 60 screw may be secured the usual name or number plate N, for use also as an operating-handle. On turning the screw-stem in one direction the locking-bolts carried by the disk l will be drawn inward by the crank action of 65 their connections with the disk, and similarly on turning the stem and disk in the opposite direction the locking-bolts will be thrown out. The thread of the stem M is so arranged that in turning the disk to throw the bolts outward 70 to lock the door the disk l will be moved inward longitudinally with the screw-stem and the inner ends of the locking-bolts will be moved correspondingly. As these bolts bear at x against their guiding-lugs l' the beveled 75 ends of the bolts will be pressed outward against the inner flaring edge of the opening in the front plate, thus drawing the door down tightly over the conical or flaring flange b of the front plate. 80

I prefer to affix to the lugs l' a plate p, to protect these parts from the action of the products of combustion.

I claim as my invention—

1. The combination of the front plate of a 85 smoke-box, having around its door-opening a flaring flange, with a sheet metal door having a flange to embrace and bear against the flaring portion of the flange of the front plate to form a tight joint therewith, and locking devices for the door, all substantially as described.

2. The combination of the front plate of a 90 smoke-box, having around its door-opening a flaring flange, with a door having a flange to 95 make a tight joint therewith, and carrying internal locking-bolts with beveled ends to bear against the inside of the front plate.

3. The combination of a smoke-box and its door with a screw-stem and disk and bolts pivoted thereto, and guide-lugs for the bolts, which bear against the inside of the front plate to lock the door.

4. The combination of the sheet-metal front plate of a locomotive smoke-box, having lugs formed in one piece with it, with a flanged door having lugs in one piece with it, and an

intermediate hinge-piece and pins, all substantially as described.

In testimony whereof I have signed my name to this specification in the presence of two subscribing witnesses.

GEORGE S. STRONG.
